UNITED STATES PATENT OFFICE.

BESSIE M. CHESTER, OF LONGBEACH, CALIFORNIA.

DESIGN FOR A WOVEN PALM-LEAF BASKET.

45,790.

Specification for Design.

Patented May 19, 1914.

Application filed March 7, 1914. Serial No. 823,577. Term of patent 7 years.

To all whom it may concern:

Be it known that I, BESSIE M. CHESTER, a citizen of the United States, residing at Longbeach, in the county of Los Angeles and State of California, have invented a new, original, and ornamental Design for Woven Palm-Leaf Baskets, of which the following is a specification, reference being had to the accompanying drawing, forming a part thereof, and in which—

Figure 1 is a plan and Fig. 2 is a side elevation of a basket illustrating my new design.

I claim:—

The ornamental design for a woven palm leaf basket as shown.

BESSIE M. CHESTER.

Witnesses:

BESSIE COLEMAN,
C. W. CHESTER.
